POWER-OPERATED COUNTER.

1,409,188.

Specification of Letters Patent. Patented Mar. 14, 1922.

Application filed April 7, 1920. Serial No. 371,889.

To all whom it may concern:

Be it known that we, LEON E. LA BOMBARD, a citizen of the United States, and resident of Chelsea, in the county of Suffolk, 5 State of Massachusetts, and MELVIN H. SIDEBOOTHAM, a citizen of the United States, and resident of Cliftondale, in the county of Essex and State of Massachusetts, have invented certain new and useful Improvements 10 in Power-Operated Counters, of which the following is a specification.

This invention relates to mechanical counters and has particular reference to that type of devices which are attached to machines for making articles such as flat paper boxes or cartons and effect counting of such articles by indicating to an attendant that a predetermined number (such as fifty) are ready to be picked for boxing or laying aside 15 in piles or groups. Usually the articles issue from the making machine either to mechanism which assembles them in a vertical pile, or onto a belt which moves so slowly that the articles rest thereon in inclined overlapping condition, such belt forming a travelling platform from which the attendant removes the articles in groups for packing. The machine produces the articles too rapidly for anyone to count them 20 individually and therefore several devices have been proposed to so change the position of some of the articles arriving in the pile or row, relatively to the intervening ones, as to indicate to the attendant where 25 to effect a separation of the pile or row in order to remove a predetermined number, such as fifty. If the device changes the position of more than one article at each displacing operation, the attendant can not determine accurately where to effect the separation, and is liable to pick up 30 or 49 or 48 articles. The smaller the articles, the greater is the liability of displacing two or more articles instead of one.

45 The principal object of the present invention is to provide mechanism of the character described which, even when the small-

est sizes of flat folded boxes are to be counted will, when operating to designate the last of a group, act upon but one box.

50

With this object in view the invention consists in a counter having a movable member which is moved by every passing article and which itself acts to displace some of them at intervals, and means connected with 55 said member to determine the periods when that member shall act. In the embodiment of the invention illustrated, the displacing means comprises a pair of rolls between which the articles pass, said rolls being shifted aside to displace one article passing between them at a time which is determined by the number of preceding articles which passed between said rolls.

60

One embodiment of the above described 65 invention is explained in our application filed February 6, 1920, Serial No. 356700 in which the mechanism for effecting the selective displacing is carried by a laterally swinging arm. In the present illustrated 70 embodiment of the invention the displacing mechanism is carried by a laterally movable slide by means of which, in connection with other features of our invention, the counter as a whole is simplified and is capable of operating at a higher rate of speed. For instance, so far as we are aware, no 75 counter has heretofore been produced which would accurately designate groups of boxes folded and passing at the speed attained 80 by the folding machine described in our application filed May 5, 1920, Serial No. 380,326. The present counter, with that folding machine, has demonstrated accurate counting of boxes passing at a rate exceeding 85 75,000 an hour. Hence sensitiveness and quickness of action of the counter are required.

Of the accompanying drawings:

Figure 1 is a perspective view of the counter, with the casing or frame partly broken away.

Figure 2 represents a vertical transverse section of the counter.

Figure 3 is a sectional plan view.

Figure 4 is a sectional perspective of a portion of the casing.

Figure 5 represents a transverse section 5 of the floor of the casing.

Figure 6 is a detail perspective view of two members of the friction driver.

Figure 7 is a perspective view of one of the ratchets and the cam connected thereto. 10 Similar reference characters indicate similar parts in all of the views.

The frame of the device comprises a box-shaped casting 12 having an arm 13 apertured for one or more screws or bolts by 15 means of which the counter is secured to a suitable part of a machine such as a box folding machine not necessary to illustrate. The articles to be counted, such as flat-folded boxes or cartons that are being made by such 20 folding machine, are fed through a throat or passageway 14 one end of which is flared as at 15. The articles are fed into the mouth 15 and through the throat 14 in rapid succession by suitable means such as the usual belts 25 (not shown) employed for delivering boxes from the folding devices.

Secured to the lower edges of the side walls of the frame 12 are two strips 16 which 30 support a slide 17. As it is quite essential, for rapid operation, that the slide 17 shall be able to move with the least possible friction we preferably construct it and the strips 16 with grooved edges, a series of anti-friction balls 18 being mounted in the grooves. 35 And to reduce the momentum and inertia of the slide, it is preferably formed with openings as at 19 (Figs. 1 and 2).

Depending from the slide 17 and movable with it is a thin web 20 having a bearing for 40 a shaft 21 carrying a roll 22 at one end and a pulley 23 at the other end. A spring 24, best illustrated by dotted lines in Figure 2, is so connected to the web and frame as to exert a constant tendency to shift the parts 45 which are carried by the slide in the direction of arrow *a* of Figure 1.

Supported by the slide and web is a vertical spindle 25 having a bevel pinion 26 meshing with a bevel pinion 27 carried by shaft 50 21. It is to be understood that in use a constantly driven belt engages pulley 23 so as to act through the shaft to rotate the roll 22 in the direction of arrow *b* (Fig. 1). Through the bevel gearing the spindle 25 is 55 also constantly driven.

Loosely mounted on the spindle above the slide are upper and lower ratchet wheels 28, 29, and a cam 30, said wheels and cam being secured together by means such as one or 60 more pins 31 (Figs. 3 and 7). Said wheels and cam are frictionally rotated as presently described. The lower wheel 29 rides on a ball bearing 32 (Fig. 2). Mounted on the upper portion of the spindle is a disk 33, a 65 friction washer 34 of leather or other suit-

able material being interposed between the disk 33 and the upper ratchet wheel. The hub 35 of disk 33 is slotted as at 36 to receive a transverse pin 37 of the spindle (Fig. 6), said slots being wider than the diameter 70 of the pin 37 to enable the disk 33 to have a limited rotary movement on the spindle for a purpose to be explained.

A collar 38 engages a screw threaded portion of the spindle and is preferably locked 75 in adjusted position thereon as by a set screw 39 (Fig. 2). A spring 40 is coiled around the hub 35 and at its ends bears upon, without being secured to, the under face of collar 38 and the upper face of disk 33. The function of this spring is two-fold as will be explained hereinafter.

An upper roll 41 which will be lifted by every article passing between it and the roll 22 is mounted to rotate freely on the 85 outer end of a lever 42 which is pivoted at 43 to a bifurcated arm 44 carried by the slide 17. A spring 45 acts to tilt said lever to yieldingly hold the roll 41 down.

Secured to, or a part of, the lever, is a 90 pawl arm 46 having its tip or tooth 47 shaped to engage and arrest one or the other of the two ratchet wheels 28, 29. Normally the spring 45, acting on the lever 42, holds the tooth 47 in engagement with the upper 95 ratchet wheel 28, but said tooth is wide enough so that just before it leaves a tooth of the upper wheel, due to a passing article causing the lever to tilt, the lower edge of said pawl tooth reaches position to form a 100 stop for a tooth of the lower ratchet wheel 29. As indicated in Figure 1, the teeth of the two ratchet wheels are so related as to be alternately stopped by the pawl tooth, the teeth of the upper wheel being above the 105 spaces between the teeth of the lower wheel.

The mechanism just described operates as an escapement device to permit intermittent rotation of the cam 30 under the impelling influence of the friction drive mechanism which consists of the friction disk 34 and the constantly rotating disk 33, the tendency of rotation being in the direction of the arrow *c* in Figure 3.

In alignment with the space between the 115 ratchet wheels (Fig. 2) is a fixed thin flat lug 48 carrying a small roll 49 and having a shoulder or tip 50 in horizontal alignment with the roll 49 and with the cam 30 (Figs. 1, 2, 3 and 4). An adjustable stop such as a 120 screw 51 is in alignment with a lug 52 at the inner end of the slide 17.

The operation is as follows:

The front end of each article passing 125 through the throat 14 and entering between the rolls 22, 41, effects sufficient lifting of the roll 41 and consequent tilting of the lever 42 to shift the pawl tooth 47 from the upper ratchet wheel 38 to the lower ratchet wheel 39, and when such article has passed 13

the rolls, the spring 45 returns the lever to normal position. Each passing article permits, in this manner, a step-by-step rotation of the two ratchet wheels and the interposed cam 30. Since the slide 17 carries all of the parts just mentioned and the other parts immediately related thereto, and since the spring 24 exerts a constant tendency to shift all of these parts toward the right (Figs. 2 and 3) the cam 30 is held in peripheral contact with roll 49. As the cam rotates step-by-step in the direction of the arrow *c* in Figure 3, and rides over said roll 49, the result is to gradually push the slide 17 and all parts carried thereby toward the left in opposition to the spring 24. The slow movement of the rolls 22, 41, in this direction does not in any degree affect the passing articles, as said rolls simply engage the articles at different distances from their edges without diverting them from the path in which they are being carried.

Assuming, for instance, that each ratchet wheel has twenty five teeth, then the cam will be permitted to be rotated by its friction drive once during the passage of twenty five articles. When the tip or high point of the cam not only passes the roll 49 but also the tip 50 of the fixed lug 48, the spring 24 acts to instantly shift the slide 17 and all parts carried thereby, including the rolls 22, 41, to the right, to a point determined by the screw stop 51. The parts are so proportioned that, since the movement of the ratchet wheels and the cam are initiated when the front end of an article lifts roll 41, the tip of the cam passes the tip 50 and spring 24 acts before that same article entirely passes the rolls 22, 41. Therefore, since the spring 45 causes the upper roll to act on the article with a considerable grip, the sudden movement of the slide and the rolls 22, 41, to the right pulls the twenty fifth article, and only that one, out of the line of those which preceded it. In other words the article which is displaced is the one which causes displacing action of the device after an exact predetermined number of articles have preceded it. Of course the articles which follow the displaced one are engaged by the rolls 22, 41, nearer the edges of said articles than the displaced one, but that does not cause them to be shifted laterally from their normal line of travel. Then as the cam rotates as the result of the passing of those following articles, the slide and said rolls are gradually shifted back to position ready to effect lateral displacements of the next twenty-fifth article.

The reason for the tip 50 at one side of the roll 49 is that if the roll alone were depended upon for coaction with the cam, it would have to be exceedingly small to let the tip of the cam pass it quickly. In fact the roll

49 might be dispensed with but for the desirability of reducing as far as possible the friction between the cam and the element against which it rides.

Reference has been made to the slots 36 in the hub of the friction driving disk being wider than the diameter of the pin 37 which drives it, and to the fact that the ends of the spring 40 are not positively connected to anything. Said spring is under sufficient compression to cause the disk 33 to press the washer 34 upon the upper face of ratchet wheel 28 to effect friction drive of the latter when permitted by the oscillating pawl tooth 47, and the spring has the following additional function:—

The spring rotatively connects the spindle 25 with the disk 33, owing to the frictional bearing of its ends on said disk and the collar 38, and so the spring serves to yieldingly transmit the constant rotary movement of said spindle to the disk somewhat as it would if the pin 37 were omitted and the ends of the spring connected positively instead of frictionally to the collar and disk. 90 This rotary movement exerts a constant tendency to tighten or "wind up" the spring because the ratchet wheels are held back by the pawl 46, and the friction washer 34 retards rotation of the disk 33. Then when 95 the pawl shifts to release the ratchet wheel which it was holding, the spring imparts a quick action to the disk due to the effort of the spring to unwind, and this action is instantly transmitted through the friction 100 washer to the ratchet wheels and cam. Said quick action is particularly advantageous when the last of the predetermined number of articles is passing and the tip of the cam is just about to pass the tip 50 of lug 48 to 105 release the slide and effect displacement of said last article. The purpose of the pin 37 and the relatively wide slots 36 in the hub of the disk 33 is to limit the extent or degree of winding up action that can be imparted to 110 the spring. Moreover with said pin and slot connection it is not necessary to positively connect the ends of the spring to the collar and disk and therefore it is easier to assemble, or make repairs in case a new 115 spring is needed.

Having now described our invention, we claim:

1. The combination with a guide-way for articles to be counted, of a slide movable in 120 a direction at an angle to said guideway, a member carried by the slide in position to be acted upon by each passing article, and mechanism under the control of said member to effect an article-displacing movement of 125 said slide when the last one of a predetermined number of passing articles acts upon said member.

2. A device of the character described comprising a pair of members for engaging 130

articles passing between them, a slide carrying said members, and means controlled by one of said members for shifting the slide and said members periodically at predetermined times to displace articles at spaced points.

3. A device of the character described comprising a pair of rolls for engaging articles passing between them, a slide carrying said rolls, and means controlled by one of said rolls for shifting the slide and said roll periodically at predetermined times to displace articles at spaced points.

4. A device of the character described, comprising a slide carrying a member mounted to be moved by each of a series of passing articles, means for actuating said slide to cause said member carried thereby to displace some of the articles at intervals, and means connected with said member to determine the periods when the slide and its article-displacing member shall act.

5. A device of the character described, comprising a slide carrying a member mounted to be moved by the front portion of each of a series of passing articles, and means controlled by the number of times that said member is moved for effecting a displacing movement of that member in another direction.

6. A counter mechanism of the character described having, in combination, a pair of rolls for the passage of articles between them, a slide carrying said rolls, and means cooperating with said rolls to effect movement of the slide and its rolls to laterally displace some of the articles at predetermined intervals.

7. A counter mechanism of the character described having, in combination, a pair of rolls for the passage of articles between them, a slide carrying said rolls, means for moving said slide and its rolls periodically to displace individual articles, and means controlled by the parting movement of the rolls to effect movement of the slide and said rolls in an article-displacing direction.

8. A counter having a toothed wheel, a friction driver for said wheel, a detent for said wheel, a member connected with said detent and mounted to be moved by each of a series of passing articles to effect release of the wheel, and means controlled by the wheel to cause said member to displace some of said articles at intervals.

9. A counter having a toothed wheel, a friction driver for said wheel, a detent for said wheel, a member connected with said detent and mounted to be moved by each of a series of passing articles to effect release of the wheel, and means controlled by the wheel to cause said member to displace one of the articles upon each complete rotation of said wheel.

66 10. A counter having a toothed wheel, a

friction driver for said wheel, a spring, means for actuating the driver through the medium of said spring, a detent for said wheel, a member connected with the detent and mounted to be moved by each of a series of passing articles to release the wheel to permit said spring to effect a quick partial rotation to the wheel, and means controlled by the wheel to cause said member to displace one of the articles upon each complete rotation of the wheel.

11. A counter having a pair of rolls one of which is movable relatively to the other to be moved by each of a series of articles passing between them, a laterally movable support for said rolls, a toothed wheel and a friction driver therefor carried by said support, a detent connected with the movable roll and constructed and arranged to permit intermittent actuation of the toothed wheel by the friction driver, and means controlled by said wheel to cause the said support to shift at predetermined intervals.

12. A counter having a pair of rolls one of which is movable relatively to the other to be moved by each of a series of articles passing between them, a laterally movable support for said rolls, a toothed wheel and a friction driver therefor carried by said support, a detent connected with the movable roll and constructed and arranged to permit intermittent actuation of the toothed wheel by the friction driver, a cam connected to rotate with said toothed wheel, an abutment for said cam, and a spring for shifting said support when the higher portion of the cam passes said abutment.

13. In a counter mechanism of the character described, a slide, a pair of rolls carried thereby, one of said rolls being pivotally supported by the slide, a driven spindle mounted in the slide, a toothed wheel and a cam loosely mounted on the spindle, a friction driver for the toothed wheel and cam, said driver being operatively connected with the spindle, an abutment for the cam, a detent for the toothed wheel connected with the pivotally supported roll, and a spring normally holding the slide with the cam in contact with said abutment.

14. In a counter mechanism of the character described, a slide, a pair of rolls carried thereby, one of said rolls being pivotally supported by the slide, a driven spindle mounted in the slide, a toothed wheel and a cam loosely mounted on the spindle, a friction driver for the toothed wheel and cam, said driver having a yielding connection with the spindle, an abutment for the cam, a detent for the toothed wheel connected with the pivotally supported roll, and a spring normally holding the slide with the cam in contact with said abutment.

15. A counter comprising a guideway for the articles to be counted, a slide mounted to

reciprocate at an angle to said guideway, a spring for moving the slide in one direction, a driven shaft carried by the slide and having a roll, a lever carried by the slide and 5 having at one end a roll to coact with the first mentioned roll, a spindle carried by the slide and geared to the driven shaft, a toothed wheel and a cam loosely mounted on the spindle, a friction driver for said wheel

and cam operatively connected with the 10 spindle, a detent pawl for the toothed wheel carried by said lever, and an abutment for said cam.

In testimony whereof we have affixed our signatures.

LEON E. LA BOMBARD.
MELVIN H. SIDE BOTHAM.
